UNITED STATES PATENT OFFICE

2,264,506

FUR CLEANING DEVICE

Joseph I. Blanck, Brooklyn, N. Y.

Application June 4, 1938, Serial No. 211,927

2 Claims. (Cl. 15—90)

This invention relates generally to a fur cleaning device, but more specifically to fur cleaning drums wherein provision is made for the automatic and intermittent release of germicidal and fungicidal fluids.

The main object of the invention resides in the provision, in a fur cleaning drum, of a receptacle holding a germicidal or fungicidal fluid whereby the frictional material such as saw-dust used in cleaning the furs becomes saturated with the germicidal fluid in order to kill off fungi germs and bacteria which might be present in the fur pieces.

A further object of the invention resides in the provision of a receptacle mounted within a fur cleaning drum for purposes of holding and automatically releasing germicidal and cleaning fluids, the said receptacle having inlet means for replenishing the supply.

These objects and other incidental ends and advantages of the invention will hereinafter appear in the progress of the disclosure and as pointed out in the appended claims.

Accompanying this specification is a drawing showing a preferred form of the invention wherein corresponding reference characters designate corresponding parts throughout the several views and wherein:

Figure 1 is a side view in elevation partly in section showing a conventional form of a fur cleaning drum containing a germicidal fluid receptacle mounted therein.

Figure 2 is a sectional view of Figure 1 along the plane 2—2 thereof.

Figure 3 is a side view in elevation partly in section similar to Figure 1, except that the germicidal fluid receptacle is modified in construction and in the mounting thereof.

Figure 4 is a sectional view of Figure 3 through the plane 4—4 thereof.

In accordance with the invention and a preferred form thereof shown in the drawing, numeral 10 indicates the conventional external casing of a fur cleaning drum having casing supports 11 mounted on a base 31. A drive shaft 12 rotatably mounted on one casing support penetrates casing 10 and is provided at the external end with a driving pulley 13, the said driving pulley being connected to any power source such as by a belt or by a system of gearing. The inner end of drive shaft 12 is secured to one wall of drum 14. 12' represents a complementary shaft in alignment with drive shaft 12 and is rotatably mounted on the other casing support 11, the said shaft penetrating casing 10 and being affixed to

the outer surface of a side wall of drum 14. The drum is provided with an opening over which is mounted a sliding cover therefor 15', while the casing 10 is similarly provided with an opening over which is mounted a sliding cover 16, the latter having a handle 17 secured thereto. The opening for sliding cover 15 and the opening for sliding cover 16 are preferably in face to face relationship.

10 A germicidal fluid and/or cleaning receptacle 18 is secured to and, preferably, centrally of the inner surface of a side wall of the drum, thereby being proximate to the openings of casing 10 and drum 14. An outlet 19 is secured to the lower side of receptacle 18, while the upper side is provided with a filling pipe 20 which extends to a point proximate to screen 15, filling pipe 20 being provided at its end with a cap 20' whereby receptacle 18 may be replenished when exhausted of its contents by means of a funnel.

In operation, drum 14 rotates with shafts 12 and 12' and during such operation the fur pieces contained therein come into intimate contact with a cleaning frictional material such as saw-dust 30 within the drum. As the drum rotates, the receptacle 18 will automatically release germicidal fluid either alone or in combination with a cleaning fluid whenever the outlet 19 is in its lower vertical position. In this manner, the saw-dust 30 is fed either the germicidal fluid or a combination of germicidal and cleaning fluid, thereby imparting to the saw-dust cleaning and germicidal properties.

35 In Figures 3 and 4, a modified form of receptacle is shown, the said receptacle having special mounting means within the drum 14. Thus, receptacle 18' is provided with an outlet or drip tube 19' at the bottom thereof and a filling pipe 20'', the said filling pipe 20'' having a closure cap 20a. The receptacle 18' is mounted on an adjustable and stationary bracket 21, one terminal 27 of the bracket being supported on drive shaft 12, while the other end 22 is outwardly turned and penetrates shaft 12'. Outwardly turned portion 22 of bracket 21 near the outer end has a square shank 23, while the outer end itself is threaded. A fastening member 25 having a plurality of pins 24 projecting from the inner face is adapted to be mounted on the square shank 23, the pins 24 penetrating recesses 28 in the support 11. The member 25 is secured in place by means of a wing nut 26. In this fashion, bracket 21 remains stationary during revolution of drum 14, the alternate positions of the said bracket being effectuated by movement of fastening member 25

in alternate positions by means of pins 24 and recesses 28.

The receptacle 18' is preferably mounted on a pivot 29 secured to the uppermost and middle portion of bracket 21 as shown in Figures 3 and 4. The purpose of providing alternate positions for bracket 21 is to enable the operator to refill receptacle 18' at a point adjacent to the openings in the casing and drum.

If the receptacles 18 or 18' contain germicidal fluid alone, then it is advisable that saw-dust 30 within the drum 14 be saturated with cleaning fluid. Moreover, the receptacle 18' must have an outlet 19' which delivers its fluid contents intermittently in drip fashion since it is pivotally mounted and outlet 19' is always in downwardly vertical position.

I wish it understood that minor changes and variations in the material, construction, position, integration and relative positions of the several parts may all be resorted to without departing from the spirit of the invention and without departing from the scope of the appended claims.

It is to be observed that the step of adding a germicidal and/or fungicidal agent to a cleaning fluid for purposes of sterilizing and immunizing the fur pieces during the cleaning operation is in keeping with the modern trend of prevention of the spread of disease. The hereinbefore described method has been developed whereby a cleaning fluid or agent acts as a medium for a

germicidal and fungicidal agent to enable the latter agents to penetrate the pores and interstices of the fur and skin. Since most cleaning agents are highly volatile, it is necessary to provide means of replenishing the cleaning agent to distribute and carry the germicidal and fungicidal agent for absorption and retention by the fur pieces. Thus, the saw-dust 30 may be charged with both a cleaning fluid or agent and a germicidal and fungicidal agent and the receptacles 18-18' may have only the cleaning fluid therein for purposes of replenishing the volatilized cleaning fluid in the saw-dust. The degree of absorption and retention of the fungus and germ killing compounds by the fur pieces measures the degree of sterilization and immunization thereof respecting fungi, germs and bacteria.

I claim:

1. In a fur cleaning device including a casing and a rotating drum therewithin, a receptacle for containing germicidal and cleaning fluids and having an inlet and a gravity-acting discharge member, the said receptacle being disposed inside the drum internally of the drum.

2. In a fur cleaning device including a casing and a rotating drum therewithin, a receptacle for containing germicidal and cleaning fluids secured to the inner surface of a drum wall, the said receptacle having an inlet and a gravity-acting discharge member.

JOSEPH I. BLANCK.
